(57) **CLAIM**

The ornamental design for a hand portable air compressor, as shown and described.

DESCRIPTION

FIG. 1 is a perspective view of a hand portable air compressor showing my new design.

FIG. 2 is a front view of a hand portable air compressor according to FIG. 1.

FIG. 3 is a rear view of a hand portable air compressor according to FIG. 1.

FIG. 4 is a left side view of a hand portable air compressor according to FIG. 1.

FIG. 5 is a right side view of a hand portable air compressor according to FIG. 1.

FIG. 6 is a top view of a hand portable air compressor according to FIG. 1; and,

FIG. 7 is a bottom view of a hand portable air compressor according to FIG. 1.

1 Claim, 5 Drawing Sheets
